(57) **CLAIM**

We claim the ornamental design for a mounting bracket, as shown and described.

DESCRIPTION

FIG. 1 is a perspective view of a mounting bracket of the present invention;

FIG. 2 is a right side plan view of the mounting bracket of FIG. 1;

FIG. 3 is a front plan view of the mounting bracket of FIG. 1;

FIG. 4 is a top plan view of the mounting bracket of FIG. 1;

FIG. 5 is a bottom plan view of the mounting bracket of FIG. 1;

FIG. 6 is a left side view of the mounting bracket of FIG. 1; and,

FIG. 7 is a rear plan view of the mounting bracket of FIG. 1.

The broken line showing of structure is for illustrative purposes only and forms no part of the claimed design.
